UNITED STATES PATENT OFFICE.

WILLIAM E. S. COYNE, OF SPOKANE, WASHINGTON, ASSIGNOR OF ONE-TENTH TO J. W. CODD, OF SPOKANE, WASHINGTON, AND ONE-TENTH TO COYNE HELICOPTER AIRSHIP COMPANY, OF SPOKANE, WASHINGTON.

PROPELLER.

1,294,624.

Specification of Letters Patent. Patented Feb. 18, 1919.

Application filed July 5, 1912, Serial No. 707,806. Renewed September 3, 1918. Serial No. 252,504.

To all whom it may concern:

Be it known that I, WILLIAM E. S. COYNE, a citizen of the United States, residing at Spokane, in the county of Spokane and 5 State of Washington, have invented certain new and useful Improvements in Propellers, of which the following is a specification.

The propeller which is the subject of the present invention is designed to prevent the 10 radial flow of water, due to centrifugal force, past the tips of the blades or flukes of the propeller, and also to utilize this radial flow in the propulsive effect, whereby 15 a propeller of maximum efficiency is produced.

With these objects in view, the invention consists in a novel construction and arrangement of part to be hereinafter described and 20 claimed, reference being had to the accompanying drawing forming a part of this specification, in which drawing—

Figure 1 is a plan view of the propeller;

Fig. 2 is an elevation thereof, and

Fig. 3 is an end view.

Referring specifically to the drawing, 5 denotes the hub of the propeller. From the hub radiate the blades or flukes 6, which latter may be flat and straight, or have a helical twist. Two sets of blades are shown, 30 said sets being spaced longitudinally on the hub. The drawing shows two blades in each set. For propellers of larger diameter each set will have three or more blades, and the number of sets may also be varied.

35 The blades of the respective sets lie in parallel planes, and corresponding blades of the sets are connected at their tips by a transverse wall 7, which latter closes up the space between the blades at the tips thereof,

40 and serves to prevent the radial flow past said tips, thereby reducing the slip of the propeller, the radial flow being produced by centrifugal force when the propeller is in motion. The wall also projects rearward

45 from the blades of the rearmost set, so as to prevent the aforementioned radial flow past the tips of said blades.

In order to utilize the radial flow of the water to aid in the propulsive effect, the tip of each blade extends in a curve from the 50 body of the blade, as indicated at 8, said curve being entirely across the blade, and extending to the wall 7. The curve is such that the concave side thereof is astern. Thus, when the centrifugal force begins to 55 force the water radially along the blades, the water is forced not only against the walls 7, but also against the inclines formed by the curves 8, said inclines being rearward or astern. This thrust against the inclines 60 augments the propulsive effect to a considerable degree, and adds greatly to the efficiency of the propeller.

It is to be understood that the invention is not limited to marine propellers, but that 65 it may be applied with good results to aerial vessels.

I claim:

1. A propeller having its blades arranged 70 in sets which are longitudinally spaced apart, and transverse walls closing up the space between the corresponding blades of the respective sets at the tip of the blades, said walls projecting rearward from the blades of the rearmost set. 75

2. A propeller having its blades arranged in sets which are longitudinally spaced apart, and transverse walls closing up the space between the corresponding blades of the respective sets at the tip of the blades, 80 said walls projecting rearward from the blades of the rearmost set, and said blades being provided with an incline at their tips to receive the thrust of the radial flow of the medium in which the propeller operates, said incline being rearward. 85

In testimony whereof I affix my signature in presence of two witnesses.

WILLIAM E. S. COYNE.
